(57) **CLAIM**

The ornamental design for an image measuring device as shown and described.

DESCRIPTION

FIG. 1 is a front, left side, bottom perspective view of the image measuring device showing our new design;
FIG. 2 is a front, right side, top perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and,
FIG. 8 is a bottom plan view thereof.

The dashed broken lines in the drawings depict portions of the image measuring device that form no part of the claimed design. All contour lines shown in the drawings are lines representing surfaces of the solid body and form no part of the claimed design.
